PLURAL STAGE CATALYTIC AND THERMAL
CONVERSION OF HYDROCARBONS

William Herman Barcus, Drexel Hill, Pa., assignor to Sun Oil Company, Philadelphia, Pa., a corporation of New Jersey

Application December 16, 1943, Serial No. 514,444

22 Claims. (Cl. 196—49)

1

The present invention relates to treatment of hydrocarbons and especially composite hydrocarbon mixtures for conversion to more desirable products. More particularly, the invention is directed to a process for treating hydrocarbon mixtures, such as those derived from petroleum, shale, coal or like sources, comprising a series of cooperative steps functioning in such manner as to yield products of high anti-knock value suitable for use in internal combustion engines.

The invention has particular utility in the manufacture of highest grade aviation fuels, since it provides blending stock of unusually high aromaticity which imparts to fuel compositions containing the same certain characteristics heretofore difficult to attain to the extent desired for aviation gasoline, as well as other products useful as ingredients of fuels of this type.

It is now generally recognized that aromatic hydrocarbons are particularly desirable as a constituent of modern aircraft fuel, in that this type of compound imparts to the fuel characteristics for satisfactory performance under so-called rich-mixture conditions as employed in operating at high power output, such as during takeoff. Other types of hydrocarbons of high anti-knock quality, such as branched-chain paraffins, generally fail to impart the characteristics desired for performance at high power consumption although they may perform satisfactorily under lean-mixture conditions as used in low power operation such as cruising. The accelerated development in aircraft production within recent years has given rise to a critical need for large amounts of aromatic stocks suitable to provide the rich-mixture performance characteristics desired for modern aircraft fuels, and has lead to considerable investigation of possible sources and means for obtaining such stocks.

It is known that petroleum in its natural state contains aromatic hydrocarbons, usually in minor concentrations, and various methods have been proposed for recovering in sufficiently concentrated form the aromatics of boiling range useful for aviation gasoline manufacture. It is also known that aromatic hydrocarbons are formed in the cracking of petroleum hydrocarbons, particularly in catalytic cracking, and processes employing cracking to produce aromatics and various methods of refining to obtain the

2

aromatics in suitable concentration have been suggested. Nevertheless, heretofore proposed methods have been inadequate to produce, from petroleum, aromatic stocks of desired quality in the amounts needed, and although the supply of aromatic stocks has been augmented to a minor extent from sources other than petroleum, the total production of such stocks has been far short of requirements.

10 The present invention is directed to a process for producing hydrocarbon stocks of unusually high aromaticity and in large quantities from composite hydrocarbon materials of natural or synthetic origin, and it thus provides a means of 15 meeting rich-mixture performance specifications for aviation gasoline of highest quality. The invention also is useful in the manufacture of motor gasoline of high anti-knock quality or in the production of special products of high aromaticity as, for example, spirits or selected fractions 20 suitable as source material for pure aromatic hydrocarbons.

In accordance with one aspect of the invention 25 three cooperative conversion steps are employed in the particular order of catalytic:pyrolytic:catalytic operations. A vaporizable hydrocarbon charge material containing relatively high boiling hydrocarbons is passed to a catalytic operation, a portion of the reaction mixture selected 30 with respect to boiling range and composition is subjected to thermal conversion conditions in a pyrolytic step, a portion of the reaction mixture from the latter operation likewise selected with respect to boiling range and composition is subjected to catalytic reaction conditions in another 35 catalytic step and the resultant mixture is separated into products of desired boiling range including one or more products containing relatively low boiling hydrocarbons.

40 In more particularity and with respect to producing the aforesaid aromatic blending stock for aviation gasoline, the process comprises charging composite hydrocarbon material containing hydrocarbons of gas oil boiling range, with or 45 without hydrocarbons of lower or higher boiling range, to an initial catalytic reaction zone maintained under conditions effective to promote a splitting reaction and therein transforming the charge into lower boiling hydrocarbons including 50 a substantial proportion of aromatic hydrocarbons. The reaction mixture from the catalytic

zone is passed to a fractionating zone and separated into fractions, from which a fraction containing aromatic hydrocarbons at least a considerable proportion of which boil above the aviation gasoline range is selected. The last-named fraction is passed to the pyrolytic reaction zone and therein is subjected to conditions effective to transform a substantial amount of contained hydrocarbons to chemically different compounds, including the transformation of non-aromatic hydrocarbons to more readily removable components. The reaction mixture from the pyrolytic zone is sent to a second fractionating zone and separated into fractions of selected boiling range, one of which likewise contains aromatic hydrocarbons at least a considerable proportion of which boil above the aviation gasoline boiling range. This fraction is passed to the second catalytic reaction zone wherein it is subjected to conditions capable of effecting further transformation, involving the conversion of contained non-aromatic hydrocarbons either to readily removable form or to more desirable hydrocarbon compounds and the conversion of higher boiling aromatics to lower boiling aromatic hydrocarbons suitable for use in aviation gasoline. The resulting reaction mixture is passed to a third fractionating zone and separated into desired fractions including a fraction having a boiling range suitable for aviation gasoline blending stock and having a high degree of aromaticity making it particularly desirable for this purpose. In certain specific applications the process includes subjecting other fractions obtained from the various aforesaid fractionating zones to further conversion for the production of additional amounts of highly aromatic blending stock as well as other products useful as ingredients of aviation gasoline.

In order to facilitate description of the invention there is attached hereto and made a part of this specification four sheets of drawings in which:

Figure 1 illustrates the process in simple diagrammatic form.

Figure 2 is a diagrammatic flow sheet illustrating the process in more detail.

Figure 3 is a diagrammatic flow sheet showing a still more detailed embodiment incorporating various refinements.

Figure 4 is a diagrammatic flow sheet illustrating another embodiment of the process including various other refinements.

As shown by Figure 1, charge oil is fed to a catalytic conversion zone, the catalytically reacted mixture is sent to a fractionation zone and separated into fractions of desired boiling range, a selected fraction is then passed to a pyrolytic conversion zone and the resultant reaction mixture is separated into fractions in a second fractionating zone, a selected fraction from this zone is treated in a catalytic conversion operation carried out independent of the first catalytic operation and the reaction mixture from this second catalytic operation is separated into end products of desired boiling range.

Figure 2 illustrates the process in more detail and with particular reference to its use in preparing aviation blending stock of high aromaticity. In Figure 2 gas oil, or a mixture of gas oil with lower or higher boiling hydrocarbons, enters the system through line 1 and is vaporized and heated to desired temperature under conditions to prevent substantial cracking in heater 2, whence the heated vapors pass through line 3 to

a catalytic reaction zone illustrated as catalytic converter 4 and therein are contacted with a catalyst effective to convert hydrocarbons contained in the charge stock to lower boiling hydrocarbons including a substantial proportion of aromatic hydrocarbons which are higher boiling than the desired end product. The reaction mixture flows from the reaction or conversion zone through line 5 to fractionator 6, wherein the mixture is separated into fractions of desired boiling range in the usual manner. In one type of operation four fractions separately are withdrawn from fractionator 6; namely, a light gasoline fraction which passes out through overhead line 7, an intermediate fraction boiling below 550° F. as, for example, within the range of 300-500° F. and preferably within the range of 300-470° F. which is withdrawn through sidestream line 8, a gas oil cut which is withdrawn through sidestream line 9 and a bottoms fraction which leaves the fractionator through line 10.

The intermediate fraction withdrawn from fractionator 6 through line 8 preferably is the material selected for further conversion in accordance with the invention. However, it is to be understood that, if desired, this fraction may be combined with the light gasoline fraction or that fractionator 6 may be operated in such manner as to obtain the two fractions as a single wide-boiling cut and that the mixture may be utilized as feed for the subsequent thermal conversion operation. When a separate light gasoline cut is taken as illustrated in the drawing, it may be subjected to further catalytic treatment as described hereinafter for further production of products useful in aviation gasoline manufacture. The gas oil cut may be thermally cracked or used in any other desired manner and the bottoms fraction may be utilized as fuel oil.

The aforesaid intermediate fraction, or an admixture of this material and the light gasoline hydrocarbons as the case may be, flows to a thermal or pyrolytic conversion zone illustrated as thermal converter 11 which may operate in liquid phase, vapor phase or mixed phase and which may comprise any known or desired type of system for effecting thermal conversion, for example, one in which the charging stock is cracked under high pressure in mainly or wholly liquid phase at a temperature just below its critical temperature, as illustrated in Patents No. 1,825,977, October 6, 1931, and No. 1,938,406, December 5, 1933, or in systems known as Cross, Dubbs, De Florez, Holmes-Manley, True Vapor Phase, Gyro, Tube and Tank, etc. Suitable operating conditions for this step of the process will depend considerably upon the particular type of thermal conversion system employed and to an extent upon the particular charge stock employed in the process. For instance, operating temperatures may vary within the range of 750° to 1200° F. and pressures may range from atmospheric to 3000 pounds per square inch gauge, or higher. Regardless of the particular system employed it is desirable in any event, due to the refractory nature of the feed to this step of the process, to utilize relatively severe reaction conditions.

The reaction mixture from thermal converter 11 flows through transfer line 12 to fractionator 13 wherein it is separated into fractions of desired boiling range. In one type of preferred operation three fractions are taken, consisting of distillate removed through line 14 and comprising light gasoline hydrocarbons, an intermediate side-

stream cut withdrawn through line 15 comprising hydrocarbons boiling below 550° F. as, for example, within the range of 300-500° F. and preferably within the range of 300-470° F., and a bottoms product which is withdrawn through line 16. When certain types of thermal conversion systems are employed, it is desirable to return a portion of the bottom fraction to line 12 at a zone near the outlet from thermal converter 11 in order to effect a quenching action and prevent or minimize deposition of coke in transfer line 12 and in fractionator 13, and line 17 is provided for this purpose. Also, in some instances, it is advantageous to return a portion of the bottom fraction by means of line 18 to the inlet of thermal converter 11 in order to effect further conversion.

The sidestream fraction which flows out of fractionator 13 through line 15 is the preferred feed for the third conversion stage of the present process. However, as in the case of the feed to the second conversion stage, it is to be understood that the light gasoline fraction removed through line 14 also may be included as feed either by adding it to the sidestream cut or by operating fractionator 13 so as to obtain the light gasoline and intermediate hydrocarbons as a single fraction. However, as more fully explained hereinafter, such method of operation usually is disadvantageous and it accordingly is preferable to charge only the intermediate fraction of selected boiling range to the final conversion step as illustrated in the drawing. This fraction flows to heater 19 wherein it is vaporized and heated to desired temperature, after which it passes through line 20 to catalytic converter 21 wherein it is brought in contact with a catalyst suitable for effecting the desired conversion reactions.

From catalytic converter 21 the reaction mixture passes through transfer line 22 to fractionator 23 and therein is separated into any desired fractions. When the process is carried out primarily for producing a blending stock for aviation gasoline, a fraction taken as an overhead product through line 24 and boiling below about 360° F. (for example, having an end boiling point roughly of about 350° F.) serves as particularly suitable material for this purpose. An intermediate naphtha fraction of too high boiling range to be suitable for blending in aviation gasoline but which is useful as motor gasoline blending stock or as a special solvent of high aromaticity may be withdrawn from fractionator 23 through line 25 as a sidestream cut; for example, a naphtha fraction having an end boiling point of about 430° F. and having particularly good anti-knock characteristics may be obtained in this manner. The naphtha fraction may also be subjected to a further catalytic treatment in a separate step as described hereinafter in connection with Figure 4 for further production of lower boiling material suitable as aviation blending stock. Hydrocarbons boiling higher than the naphtha fraction are withdrawn from the base of fractionator 23 through line 26.

In one method of operation which is particularly advantageous when the process is carried out primarily for the production of aviation blending stock, no naphtha fraction is withdrawn as an end product through line 25 but, instead, this sidestream cut is recycled, in toto, through line 27 to the entrance to heater 19 where it mixes with the fresh feed derived from the thermal operation and thence passes to catalytic converter 21. This method of operation results in a substantial increase in yield of aviation blending

stock and generally in an improvement in its rich-mixture performance characteristics. In practicing the process in this manner it is desirable progressively to increase the severity of the reaction conditions in catalytic converter 21 from the start of operation until the flow of the naphtha fraction through line 27 has reached equilibrium conditions. This compensates for the increase in refractory nature of the combined feed to catalytic converter 21 which occurs as the proportion of the more refractory recycled naphtha in the feed increases up to the equilibrium value.

In practicing the process as described above the two catalytic conversion steps, as well as the additional catalytic steps employed in the more explicit embodiments described below, may be carried out by any suitable or known means for effecting conversions of the type desired. The catalytic contact material may be used *in situ* as a stationary catalyst bed or may be permitted to flow either countercurrently to or concurrently with the hydrocarbon vapors to effect the desired reactions. Particularly suitable arrangements of apparatus employing converters of the stationary bed type in multiplicity to provide for catalyst regeneration and continuity of operation are described in U. S. Patent No. 2,078,247, issued to Eugene J. Houdry, and U. S. Patent No. 2,031,600, issued to J. W. Harrison et al. Such arrangements have had widespread use in the industry and are particularly adaptable for carrying out each of the catalytic steps of the present invention. Somewhat similar operating conditions may be employed in each of the two above-described catalytic conversion stages, although in general it is desirable to use more severe conditions in the second catalytic operation due to the more refractory nature of the feed to this step. When stationary catalyst beds of the type described in the aforesaid patents are utilized, suitable temperatures and pressures usually lie within the ranges of 750° F. to 1000° F. and atmospheric pressure to about 100 pounds per square inch gauge, respectively. When other types of catalytic operation are employed, temperatures ranging up to about 1100° F. may be satisfactory. In the second catalytic step, it is especially desirable to utilize a relatively high pressure since this helps promote the transformation reactions involved, particularly the transformation of olefins to other hydrocarbons. Feed rates of 8/20 (8 volumes of feed liquid per hour per 20 volumes of catalyst) to 50/20 are suitable, although lower or higher rates also may be used successfully.

Similar catalysts or contact masses may be used in each catalytic operation including the additional catalytic steps of the more refined embodiments, although the reactions which are brought about in the various steps may be dissimilar to considerable extent as more fully discussed hereinafter. Catalysts of siliceous nature having high activity are preferred. These may include blends of silica and one or more metal oxides capable of assisting transformation reactions and may be derived from naturally occurring or synthetically prepared substances. Excellent results have been realized with contact masses containing blends of silica and alumina of synthetic origin or derived from naturally occurring silicates and hydrosilicates of alumina, including activated blends of silica and alumina in controlled ratio with or without other ingredients, as, for example, contact masses wherein the silica and alumina are in the weight ratio of at least 3:1, after the man-

ner described in U. S. Patents 2,078,945 and 2,078,951, issued to Eugene J. Houdry.

The chemical reactions involved in transforming the charge materials to more desirable products in accordance with the present invention obviously are very complicated and do not permit of precise explanation. However, a consideration of the predominant reactions effected in the three conversion stages is useful as an illustration of the cooperative relationship of the steps in producing products of enhanced value and of the unitary nature of the process as a whole.

The initial conversion operation carried out in catalytic converter 4 effects a splitting reaction in which gas oil hydrocarbons are converted to hydrocarbons of lower boiling range. It has been found that the reaction products include a considerable amount of aromatic hydrocarbons. These aromatics, however, are predominantly of relatively high molecular weight, mostly boiling above 300° F., and therefore are of too high boiling range for more than a minor proportion thereof to be utilizable in aviation fuel without subsequent treatment in accordance with the invention. When fresh gas oil is charged to the process and a sidestream cut having a boiling range of 300-470° F., for example, is withdrawn from fractionator 6 through line 8, this cut usually will contain 25-60 per cent aromatics, the remainder being paraffins and naphthenes with a small proportion of olefins. When this fraction is subjected to treatment in the thermal conversion step as described above, the predominant reactions effected therein appear to comprise conversion of non-aromatic hydrocarbons, particularly the paraffinic hydrocarbons, to olefins and low molecular weight paraffins without substantial formation of lower boiling aromatics. A sidestream fraction which is then withdrawn from fractionator 13 through line 15 and which has a boiling range of 300-470° F., for example, usually will contain 40-65 per cent aromatics and 15-25 per cent olefins. Treatment of this fraction in the third conversion step as described above brings about two types of transformation requisite for obtaining desired products. One type comprises conversion of a predominant amount of the olefins to other hydrocarbon compounds and involves transformation of olefins to isoparaffins which boil in the aviation gasoline range and which have good anti-knock characteristics, as well as polymerization of olefins to higher boiling materials which subsequently are separated from the desired products in fractionator 23. The other type comprises transformation of the aromatic hydrocarbons to aromatics of lower molecular weight, presumably by a dealkylation reaction, thereby forming aromatics of boiling range suitable for aircraft fuel. In addition, this treatment also appears to cause conversion of non-aromatic hydrocarbons, particularly naphthenes, either to more desirable form or to readily removable hydrocarbon compounds. As a result of these reactions the overhead fraction removed from fractionator 23 through line 24 and having a boiling range up to about 350° F., for example, usually will contain 65-85 per cent aromatic hydrocarbons. The naphtha fraction withdrawn through line 25 and having a boiling range up to 450° F., for example, also will contain aromatics in approximately the same concentration. Thus the three conversion steps cooperate in producing chemical reactions which have a cumulative and cooperating effect resulting in attainment of desired product characteristics.

Reasons for certain preferred features of the hereinbefore described method of practicing the invention are provided by the above discussion relating to the predominating chemical transformations brought about by the three conversion operations. Since a high concentration of aromatic hydrocarbons in the products are desirable and since, in the first conversion step, only a small proportion of the aromatic hydrocarbons formed boil below 300° F., it is preferable to withdraw a light gasoline fraction from fractionator 6 through line 7 and to feed only the intermediate fraction withdrawn through line 8 to the thermal conversion step. Likewise, since the reaction mixture after thermal conversion contains no substantial amount of aromatic hydrocarbons boiling below 300° F. but does contain a considerable proportion of olefins as well as naphthenes and paraffins boiling below this temperature, a light gasoline fraction preferably is withdrawn from fractionator 13 through line 14. This results in more efficient utilization of the catalytic equipment in the final conversion step.

A more extended application of the process is illustrated in Figure 3. As shown, charge oil entering the system through line 1 is heated and passed to catalytic converter 4 and the reaction mixture is separated in fractionator 6, a selected fraction preferentially boiling within the range of 300-470° F. is withdrawn through line 8 and passed to thermal converter 11 and the reaction mixture from the thermal conversion is separated in fractionator 13, a selected fraction likewise boiling within the preferred range of 300-470° F. is withdrawn through line 15 and passed through heater 19 to catalytic converter 21, all as described in connection with Figure 2. In the present embodiment the reaction mixture from catalytic converter 21 is separated in fractionator 23 into three fractions but only two of these, namely, the overhead and bottoms fractions, are withdrawn as end products of this operation. The intermediate fraction, having a boiling range, for example, of 320-450° F., is recycled in its entirety through line 27 for further conversion. The overhead product, which has an end boiling point preferably of about 350° F., may be passed through line 24 directly to storage tank 28 for use as aviation blending stock. However, it is distinctly preferable, before sending this product to storage, first to send it through line 29 to fractionator 30 and therein to separate the C₄ and C₅ hydrocarbons, which are removed through overhead line 31. It has been found that a considerable proportion of the C₄ and C₅ hydrocarbons are olefinic and that their removal therefore results in substantial improvement in acid-heat and also improves the rich-mixture performance characteristics.

The gasoline fraction derived from the initial catalytic step and having an end boiling point of about 350° F., for example, is passed through line 7 to heater 32 and thence, by means of line 33, to catalytic converter 34 wherein it is subjected to catalytic treatment under reaction conditions comparable to those hereinbefore set forth in connection with the other catalytic operations. The reaction mixture flows through line 35 to fractionator 36 and therein is separated into three fractions: namely, a light gasoline fraction of boiling range suitable for aviation base stock, for example boiling below about 310° F., which is passed through line 37 to storage tank 38; a bottoms fraction which is withdrawn through line 39; and an intermediate sidestream fraction boil-

ing within the approximate limits of 300°-470° F. which is removed through line 40.

The last-named fraction is particularly suitable charge material for still another catalytic operation in which additional quantities of aviation blending stock having even better anti-knock characteristics are produced. In this operation the fraction is passed through heater 41 and line 42 to catalytic converter 43 in which rather severe reaction conditions are employed due to the refractory nature of the feed. The reaction mixture passes through line 44 to fractionator 45, from which an overhead fraction withdrawn through line 46 and a bottoms fraction withdrawn through line 47 are obtained as end products of this step. As in a previously described step, a naphtha fraction having a boiling range, for example, of 320°-450° F. is withdrawn as a side-stream cut through line 48 and all of this fraction is recycled to heater 41 and thence to catalytic converter 43 in admixture with fresh feed supplied through line 40. This results in increased yields of the desired overhead product. As described above in connection with recycling in this manner, it is desirable upon starting operation progressively to increase the severity of reaction conditions due to the increasing refractory nature of the mixed feed until equilibrium flow conditions are reached. The overhead product withdrawn through line 46 may be passed through line 24 directly to aviation blending stock storage tank 28 but, as in the case of the aviation blending stock from fractionator 23, preferably is first sent to fractionator 30 for removal of C₄ and C₅ hydrocarbons.

In another embodiment illustrated by Figure 4, the initial catalytic step and the succeeding thermal step conform in detail to the corresponding steps described in connection with Figure 3. Likewise the catalytic step wherein the light gasoline fraction derived from the initial catalytic operation is treated in catalytic converter 34 and the reaction mixture is separated in fractionator 36 is identical with the corresponding step of Figure 3. However, the catalytic operation immediately following the thermal step differs in that the naphtha fraction, instead of being recycled to heater 19 and catalytic converter 21, is sent through line 49 to storage tank 50 for subsequent use independent of this catalytic operation. The naphtha fraction withdrawn from fractionator 36 through line 51 is passed to storage tank 52, whence, in accordance with one embodiment, it may be passed by means of line 53 to heater 19 and catalytic converter 21 for further conversion in admixture with the thermally converted feed fraction supplied through line 15. Alternatively, the naphtha fraction in storage tank 52 may be withdrawn from the system through line 54 for use as motor gasoline blending stock or other special purpose or it may be charged by means of

lines 55 and 56 to heater 41 and catalytic converter 43 for production of additional amounts of aviation blending stock. Likewise, the naphtha fraction in storage tank 50 may be withdrawn through line 57 for special use or it may be passed through lines 58 and 59 as feed to the catalytic conversion operation, either separately or in admixture with the material from storage tank 52. Preferentially, when the two naphtha fractions are utilized as feed for the final catalytic conversion step, they are charged separately and in alternate manner to heater 41 and catalytic converter 43 since somewhat more severe reaction conditions are required to bring about the desired transformation of the naphtha from storage tank 52 than required for the naphtha from storage tank 50. The overhead fraction produced in this final catalytic operation preferably is stripped of C₄ and C₅ hydrocarbons in fractionator 30 before being used as aviation blending stock.

In practicing the present invention for manufacturing aviation gasoline blending stock it is distinctly desirable that the feed material to the thermal conversion step, in addition to having a boiling range below 550° F., contain at least 25 per cent, and preferably at least 35 per cent, of aromatic hydrocarbons boiling above 300° F. When materials containing aromatic hydrocarbons in lesser amounts are charged to the thermal conversion zone, it is difficult to attain in the product the rich-mixture performance characteristics desired for aviation blending stock.

The following examples are illustrative of specific embodiments of the invention and are given only for purposes of illustration and not in limitation thereof:

Example I

The present example illustrates the embodiment shown in Figure 2 without any recycling of the naphtha fraction through line 27. A straight-run gas oil derived from a mixture of Gulf Coastal and East Texas crudes was charged to the process and subjected to reaction conditions in catalytic converter 4 which comprised a multiplicity of catalyst chambers of the stationary catalyst bed type operating alternately in on-stream and off-stream fashion. A pressure of approximately 30 pounds per square inch gauge was maintained during on-stream operation in converter 4 and the temperature within the catalyst bed varied from about 885° F. at the beginning of each on-stream period to about 825° F. at the end of each on-stream period. The feed rate was approximately 20/20. The reaction mixture was separated in fractionator 6 into four liquid fractions and, in addition, an uncondensable gas fraction. Yields and properties of the liquid products and charge stock were approximately as follows:

	Charge Stock	Light Gasoline	Naphtha Fraction	Gas Oil Fraction	Bottoms Fraction
Yield, vol. per cent of charge stock.....	100	29.0	13.8	43.1	5.5

11

The naphtha fraction was subjected to pyrolytic treatment in thermal converter 11 under temperatures and pressures varying respectively from 319° F. and 960 pounds per square inch gauge at the inlet to 978° F. and 750 pounds per square inch gauge at the outlet. The reaction mixture was separated in fractionator 13 into three liquid fractions and also an uncondensable gas fraction. Yields and properties of the liquid products were approximately as follows:

	Light Gasoline	Naphtha Fraction	Bottoms Fraction
Yield, vol. per cent of naphtha charged	15	54	18
A. P. I. gravity	76.6	33.5	22.2
A. S. T. M. distillation:

Anti-knock rating:			
A. S. T. M. Motor Method Octane No. (clear)	77	78.5	
1939 Research Method Octane No. (clear)		88.1	

The resulting naphtha fraction was treated in catalytic converter 21, which was similar in type

12

As shown by the data listed for the stabilized blending stock, this product was of high quality and suitable for use in manufacture of aviation gasoline meeting highest present-day standards.

Example II

This example also illustrates the embodiment shown in Figure 2 but with recycling of the total naphtha fraction through line 27. The naphtha fraction derived from the thermal operation and conforming substantially to that shown in Example I was fed to heater 19 and treated in catalytic converter 21. All of the naphtha fraction withdrawn through the sidestream line from fractionator 23 was recycled through line 27 to give, as charge to the operation, an admixture of recycled naphtha and the fresh feed. A pressure of 55-60 pounds per square inch gauge and a temperature varying from 885° F. to 835° F. were maintained in catalytic converter 21. The fresh feed rate was 11.7/20 and the combined feed rate was 15.7/20. C₄ and C₅ hydrocarbons were removed from the overhead product and a stabilized blending stock thereby was obtained. Properties and yields of the charge materials and the liquid products were approximately as follows:

	Charge			Stabilized Blending Stock	Bottoms Fraction
	Fresh Feed	Recycled Naphtha	Total Feed		
Yield, vol. per cent of fresh feed	100	34	134	55.4

to catalytic converter 4, at a pressure of approximately 35 pounds per square inch gauge and a temperature varying from 910° F. at the beginning of on-stream operation to 845° F. at the end of the on-stream period. A feed rate of 15.7 was utilized. The reaction mixture was separated in fractionator 23 into three fractions. The overhead fraction was subjected to distillation effecting removal of C₄ and part of the C₅ hydrocarbons, thereby producing a stabilized aviation blending stock. Yields and properties of the products were approximately as follows:

It is to be noted that the stabilized blending stock had substantially improved anti-knock quality over that shown in Example I. The yield in the present case was slightly lower than in Example I but this was due to the lower end boiling point of this product in the present example. In a further operation in which the stabilized blending stock had substantially the same end boiling point as in Example I, the yield increased to 61.5 per cent. A comparison of Examples I and II thus indicates that recycling has the effect of increasing both yield and quality.

Example III

A light gasoline fraction derived from the initial catalytic conversion step in another operation similar to that described in Example I was subjected to catalytic treatment in catalytic converter 34 under a pressure of approximately 75 pounds per square inch gauge and a temperature varying from 855° F. to 820° F. at the beginning and end, respectively, of the on-stream period. The feed rate was 36.7/20. The reaction mixture was separated in fractionator 36 into three liquid fractions. Yields and properties of these as well as of the light gasoline charge are shown in the following tabulation:

	Charge	Overhead Fraction	Naphtha Fraction	Bottoms Fraction
Yield, vol. per cent of charge.....	100	75.0.....	10.9	4.0

As shown by the tests, the overhead fraction was particularly suitable as aviation base stock. The naphtha fraction was passed through line 49 to catalytic converter 43 wherein it was subjected to catalytic conversion under a pressure of approximately 65 pounds per square inch gauge and a temperature varying from 890° F. to 850° F. at the beginning and end, respectively, of the on-stream period. All of the naphtha fraction separated from the reaction mixture in fractionator 45 was recycled through line 48 to heater 41 and catalytic converter 43, so that the only liquid fractions obtained as end products were the overhead and bottoms. The charge rate to catalytic converter 43 was 13.1/20 based on the fresh feed from line 40 or 15.7/20 based on the combined fresh feed and recycled naphtha. Yields and properties of the two end products as well as of the recycled naphtha were as follows:

¹ After removal of light ends in fractionator 30.

² Calculated from 50:50 blend with aviation base stock.

The data tabulated for the overhead fraction show it to be excellent aviation blending stock.

The aviation blending stock prepared in accordance with the present invention may be utilized in any suitable or desired proportion as an ingredient of aircraft fuel. However, when it is prepared so as to contain a substantial amount of hydrocarbons boiling above 300° F. as in the specific examples presented, it is desirable to em-

ploy a minor proportion, for instance 10 per cent, in the blend in order that the usual distillation specifications for aircraft fuel may be met. Such minor proportions usually bring about the desired improvement in rich-mixture performance characteristics.

Although it has been stated above that the various catalytic conversion steps may be carried out by any of the known means for effecting such conversions, it is not meant to imply that the various types of catalytic operation are exact equivalents, since the different methods may differ to an extent in effectiveness in promoting the various transformation reactions involved in the process. For example, in the catalytic step imme-

diately following the pyrolytic conversion, a relatively high operating pressure helps to bring about more complete conversion of the olefinic hydrocarbons; accordingly, the stationary catalyst bed method, which generally permits the use of pressures higher than those employed in other methods, may be more advantageous in this respect. The so-called "adiabatic" type of catalytic operation, wherein no heat exchange medium is employed to regulate the catalyst temperature and the only gain or loss of heat in the catalytic zone is that due to the temperature difference between inlet and outlet reactant streams, may be used to advantage in certain respects. The choice of type of catalytic operation also may be governed by considerations not directly connected with the present process, such as the proper integration of the process with other refinery operations. For example, the method com-

monly referred to as the "fluid catalyst method," in which vapor containing particles of finely divided catalyst suspended therein is passed through a reaction zone to effect the desired conversion, tends to produce a greater proportion of butylenes in the gaseous conversion products whereas the stationary bed method tends to produce a greater proportion of isobutane. It therefore may be desirable to choose the type of cata-

lytic operation on such basis as to compensate for a deficiency of either butylenes or isobutane from other refinery operations and so obtain a proper balance between these components as feed to a separate alkylation process. Again, since a light gasoline fraction is produced in the first catalytic stage and this fraction may be subsequently treated catalytically in order to produce aviation base stock, it may be desirable to choose for the initial step the method of operation which produces the best quality light gasoline fraction for such purpose.

Although the flow sheets show a multiplicity of catalytic zones, in actual practice the various conversions may be and preferably are carried out with a minimum amount of catalytic equipment by utilizing "blocked out" operation. In operating in this manner one catalytic unit is utilized to effect a number of the various conversions by charging first one feed fraction over a reasonably extended time period and then another. Fractions produced in the various operations and which are intended for further conversion are collected separately in storage tanks and later utilized as feed as desired. In practicing the invention on commercial scale the catalytic steps including all those in the more specifically illustrated forms of the process conveniently may be carried out with two catalytic units, one continuously charging the fresh gas oil and the other handling the various other catalytic conversions in "blocked out" operation. The present process when carried out in this manner permits more efficient utilization of catalytic equipment and production of greater amounts of aviation fuel for a given amount of catalytic capacity than heretofore possible.

I do not herein claim the process described as being practiced in the apparatus diagrammed in Fig. 3, as the same forms the subject matter of a divisional application, Ser. No. 723,194, filed January 20, 1947.

What I claim and desire to protect by Letters Patent is:

1. In the production of lower boiling hydrocarbons of high aromaticity the steps of catalytically cracking a composite higher boiling hydrocarbon charge to produce a hydrocarbon mixture containing a substantial proportion of high boiling aromatics, selecting from the reaction mixture a fraction containing at least 25 per cent of high boiling aromatics, thermally cracking said fraction without substantial admixture with hydrocarbons derived from any other operation to transform non-aromatics contained therein to chemically different hydrocarbon compounds including olefins, selecting from the reaction mixture resulting solely from thermally cracking said fraction a fraction containing at least 40 per cent of high boiling aromatics and a minor percentage of olefins, catalytically reacting the last-named fraction in an independent zone in the presence of a cracking type catalyst to transform high boiling aromatics to lower boiling aromatics and reduce materially the olefin content, and separating from the mixture resulting from the last catalytic reaction a fraction containing at least 65 percent of said lower boiling aromatics as the desired product.

2. The process defined in claim 1 wherein, from the mixture resulting from the last catalytic reaction zone, is separated a naphtha of high aromaticity boiling mainly above the fraction containing the lower boiling aromatics and in which such separated naphtha is catalytically reacted

in an independent zone, in the presence of a cracking type catalyst to produce lower boiling aromatics and from the reaction mixture obtained from the independent zone a fraction is separated containing a substantial proportion of said lower boiling aromatics.

3. The process defined in claim 1 wherein a naphtha fraction boiling mainly above the fraction containing the lower boiling aromatics also is separated from the reaction mixture obtained from the last catalytic reaction zone and at least a substantial proportion of such separated naphtha fraction is recycled to said catalytic reaction zone.

4. In the production of lower boiling hydrocarbons of high aromaticity the steps of catalytically cracking a composite higher boiling hydrocarbon charge to produce a hydrocarbon mixture containing a substantial proportion of high boiling aromatics, selecting from the reaction mixture a fraction boiling below 550° F. and containing a substantial proportion of aromatics boiling above 300° F., thermally cracking said fraction alone to transform non-aromatics contained therein to chemically different hydrocarbon compounds including olefins, selecting from the reaction mixture resulting solely from thermally cracking said fraction a fraction boiling below 550° F. and containing a substantial proportion of aromatics boiling above 300° F. and a minor percentage of olefins, catalytically reacting the last-named fraction in an independent zone in the presence of a cracking type catalyst to transform the high boiling aromatics to lower boiling aromatics and reduce materially the olefin content, and separating from the mixture resulting from the last catalytic reaction a fraction containing a high concentration of said lower boiling aromatics as the desired product.

5. The process defined in claim 4 wherein, from the mixture resulting from the last catalytic reaction zone, is separated a naphtha of high aromaticity boiling mainly above the fraction containing the lower boiling aromatics and in which such separated naphtha is catalytically reacted in an independent zone in the presence of a cracking type catalyst to produce lower boiling aromatics and from the reaction mixture obtained from the independent zone a fraction is separated containing a substantial proportion of said lower boiling aromatics.

6. The process defined in claim 4 wherein a naphtha fraction boiling mainly above the fraction containing the lower boiling aromatics also is separated from the reaction mixture obtained from the last catalytic reaction zone and at least a substantial proportion of such separated naphtha fraction is recycled to said catalytic reaction zone.

7. In the production of lower boiling hydrocarbons of high aromaticity the steps of catalytically cracking a composite higher boiling hydrocarbon charge to produce a hydrocarbon mixture containing a substantial proportion of high boiling aromatics, selecting from the reaction mixture a fraction boiling predominantly within the limits of 300° F. to 470° F. and containing a substantial proportion of aromatics, thermally cracking said fraction without substantial admixture with hydrocarbons derived from any other operation to transform non-aromatics contained therein to chemically different hydrocarbon compounds including olefins, selecting from the reaction mixture resulting solely from ther-

mally cracking said fraction a fraction boiling predominantly within the limits of 300° F. to 470° F. and containing a substantial proportion of aromatics and a minor percentage of olefins, catalytically reacting the last-named fraction in an independent zone in the presence of a cracking type catalyst to transform the high boiling aromatics to lower boiling aromatics and reduce materially the olefin content, and separating from the mixture resulting from the last catalytic reaction a fraction boiling below 360° F. and containing a high concentration of said lower boiling aromatics as the desired product.

8. The process defined in claim 7 wherein a naphtha fraction boiling mainly above the fraction containing the lower boiling aromatics also is separated from the reaction mixture obtained from the last-named catalytic reaction zone and at least a substantial proportion of said fraction is recycled to the feed to said zone for further conversion.

9. The process defined in claim 7 wherein C₄ and C₅ hydrocarbons are removed from the fraction separated from the last-named reaction mixture thereby to yield a product improved with respect to acid-heat and rich-mixture performance characteristics.

10. In the production of lower boiling hydrocarbons of high aromaticity suitable for use as aviation blending stock the steps of catalytically cracking a composite higher boiling hydrocarbon charge to produce a hydrocarbon mixture containing a substantial proportion of high boiling aromatics boiling above 300° F., selecting from the mixture a fraction boiling predominantly within the limits of 300° F. to 470° F. and containing 25-60 per cent aromatics, thermally cracking said fraction without substantial admixture with hydrocarbons derived from any other operation to transform nonaromatics contained therein to chemically different hydrocarbon compounds including olefins, selecting from the reaction mixture resulting solely from thermally cracking said fraction a fraction boiling predominantly within the limits of 300° F. to 470° F. and containing 40 to 65 per cent of aromatics and a minor percentage of olefins, catalytically reacting the last-named fraction in an independent zone in the presence of a cracking type catalyst to transform the high boiling aromatics to lower boiling aromatics and reduce materially the olefin content, and separating from the mixture resulting from the last catalytic reaction a fraction boiling below about 360° F. and containing 65-85 per cent aromatics as the desired product.

11. In the production of lower boiling hydrocarbons of high aromaticity suitable for use as aviation blending stock the steps of catalytically cracking a composite higher boiling hydrocarbon charge to produce a hydrocarbon mixture containing a substantial proportion of aromatics boiling above 300° F., selecting from the reaction mixture a fraction containing at least 25 per cent of high boiling aromatics boiling within the limits of 300° F. to 550° F., thermally cracking said fraction without substantial admixture with hydrocarbons derived from any other operation to transform nonaromatics contained therein to chemically different hydrocarbon compounds including olefins, selecting from the reaction mixture resulting solely from thermally cracking said fraction a fraction containing at least 40 per cent of aromatics boiling within the limits of 300° F. to 550° F. and a minor percentage of olefins, catalytically reacting the last-named fraction in an

independent zone in the presence of a cracking type catalyst to transform the high boiling aromatics to aromatics boiling below 360° F. and reduce materially the olefin content, and separating from the mixture resulting from the last catalytic reaction a fraction containing at least 65 per cent of said lower boiling aromatics as the desired product.

12. In the production of lower boiling hydrocarbons of high aromaticity suitable for use as aviation blending stock the steps of catalytically cracking a composite higher boiling hydrocarbon charge to produce a hydrocarbon mixture containing a substantial proportion of aromatics boiling above 300° F., selecting from the reaction mixture a fraction containing 25 to 60 per cent of aromatics boiling within the limits of 300° F. to 470° F., thermally cracking said fraction without substantial admixture with hydrocarbons derived from any other operation to transform nonaromatics contained therein to chemically different hydrocarbon compounds including olefins, selecting from the reaction mixture resulting solely from thermally cracking said fraction a fraction boiling within the limits of 300° F. to 470° F. and containing at least 40 per cent of aromatics and a minor percentage of olefins, catalytically reacting the last-named fraction in an independent zone in the presence of a cracking type catalyst to transform the high boiling aromatics to aromatics boiling below 360° F. and reduce materially the olefin content, and separating from the mixture resulting from the last catalytic reaction a fraction containing at least 65 per cent of said lower boiling aromatics as the desired product.

13. In the production of lower boiling hydrocarbons suitable for aviation gasoline manufacture the steps of catalytically cracking a composite hydrocarbon charge boiling predominantly in the gas oil boiling range to produce a hydrocarbon mixture containing a substantial proportion of high boiling aromatics, selecting from the reaction mixture a light gasoline fraction and a naphtha fraction boiling mainly above the gasoline fraction and containing said high boiling aromatics, thermally cracking the naphtha fraction to transform non-aromatics to chemically different hydrocarbon compounds and selecting from the resulting reaction mixture a second naphtha fraction of similar boiling range containing the high boiling aromatics, catalytically reacting said second naphtha fraction in a second catalytic conversion zone in the presence of a cracking type catalyst to transform aromatics contained therein to lower boiling aromatics, separating from the reaction mixture resulting from the second catalytic reaction a gasoline of high aromaticity boiling mainly below 350° F. and having rich-mixture performance characteristics suitable for aviation blending stock and a naphtha fraction of high aromaticity boiling mainly above said gasoline, catalytically reacting the light gasoline fraction from the first catalytic operation in a third catalytic conversion zone in the presence of a cracking type catalyst to produce additional high boiling aromatics, selecting from the reaction mixture resulting from the third catalytic conversion zone a gasoline fraction boiling mainly below 310° F. having lean mixture performance characteristics and suitable for use as aviation base stock and a highly aromatic naphtha fraction boiling mainly above said gasoline fraction, mixing the last-named naphtha fraction with the naphtha fraction from the sec-

ond catalytic conversion zone and catalytically reacting the mixture in a fourth catalytic conversion zone in the presence of a cracking type catalyst to produce lower boiling aromatics, separating from the reaction mixture resulting from the fourth catalytic conversion zone a gasoline fraction of high aromaticity boiling mainly below 350° F. to thereby yield further amounts of product having rich-mixture performance characteristics suitable for aviation blending stock.

14. In the production of lower boiling hydrocarbons suitable for aviation gasoline manufacture the steps of catalytically cracking a composite hydrocarbon charge boiling predominantly in the gas-oil boiling range to produce a hydrocarbon mixture containing a substantial proportion of high boiling aromatics, selecting from the reaction mixture a light gasoline fraction and a naphtha fraction boiling mainly above the gasoline fraction and containing said high boiling aromatics, thermally cracking the naphtha fraction to transform non-aromatics to chemically different hydrocarbon compounds and selecting from the resulting reaction mixture a second naphtha fraction of similar boiling range containing the high boiling aromatics, catalytically reacting the second naphtha fraction in a second catalytic conversion zone in the presence of a cracking type catalyst to transform aromatics to lower boiling aromatics, separating from the reaction mixture resulting from the second catalytic reaction a gasoline fraction of high aromaticity boiling mainly below 350° F. and having rich-mixture performance characteristics suitable for aviation blending stock and a third naphtha fraction of high aromaticity boiling mainly above said gasoline fraction, catalytically reacting the third naphtha fraction in a third catalytic conversion zone in the presence of a cracking type catalyst to transform aromatics contained therein to lower boiling aromatics, selecting from the reaction mixture resulting from the third catalytic conversion zone a gasoline fraction of high aromaticity boiling mainly below 350° F. to thereby yield further amounts of product having rich-mixture performance characteristics suitable for aviation blending stock, catalytically reacting the light gasoline fraction from the first catalytic conversion zone in a fourth catalytic conversion zone in the presence of a cracking type catalyst to further produce high boiling aromatics, selecting from the reaction mixture resulting from the fourth catalytic conversion zone a gasoline fraction boiling mainly below 310° F. having lean mixture performance characteristics suitable for aviation base stock and a highly aromatic fourth naphtha fraction boiling mainly above the gasoline fraction and mixing at least a substantial proportion of the fourth naphtha fraction with the second naphtha fraction to thereby form mixed feed for the second catalytic conversion zone.

15. In the production of lower boiling hydrocarbons of high aromaticity the steps of thermally cracking a composite hydrocarbon material the predominant part of which boils within the range of 300-500° F. and containing not less than 25 per cent of aromatics boiling above 300° F. to transform a substantial part of the non-aromatics to chemically different hydrocarbon compounds including olefins without substantial transformation of higher boiling aromatics to lower-boiling aromatics, selecting from the reaction mixture resulting from the thermal operation an intermediate fraction the predominant

part of which boils within the range of 300-500° F., catalytically reacting said intermediate fraction alone in the presence of a cracking type catalyst to transform the higher boiling aromatics to lower boiling aromatics including aromatics boiling below 300° F. and greatly reduce the percentage of olefins, then separating from the reaction mixture resulting from the catalytic operation a lower boiling fraction containing substantially all the aromatics boiling below 300° F.

16. In the production of lower boiling hydrocarbons of high aromaticity, the steps of thermally cracking a composite hydrocarbon material the predominant part of which boils within the range of 300-500° F. and containing not less than 25 per cent aromatics boiling above 300° F. to transform a substantial part of the non-aromatics to chemically different hydrocarbon compounds including olefins and without substantial transformation of higher boiling aromatics to lower boiling aromatics, selecting from the reaction mixture resulting from the thermal operation an intermediate fraction the predominant part of which boils within the range of 300-500° F., catalytically reacting said intermediate fraction alone in the presence of a cracking type catalyst to greatly reduce the percentage of olefins and to transform higher boiling aromatics to lower boiling aromatics thereby to produce a mixture of a relatively large fraction of hydrocarbons boiling mainly below 350° F. and containing a major percentage of aromatics and a relatively small fraction of hydrocarbons boiling mainly above 350° F. and also containing a major percentage of aromatics, then separating from the last-mentioned reaction mixture the fraction containing the lower boiling product of high aromaticity.

17. The process defined in claim 16 which comprises catalytically reacting the fraction boiling mainly above 350° F. in the presence of a cracking type catalyst to transform the higher boiling aromatics contained therein to lower boiling aromatics thereby to increase both the amount of lower boiling hydrocarbons of high aromaticity and the percentage of aromatics contained in the low boiling product.

18. The process of producing from a hydrocarbon charging stock boiling mainly within the range of 400-800° F. and relatively poor in aromatics a lower boiling hydrocarbon aviation blending stock the major portion of which consists of aromatics, which comprises catalytically cracking the charging stock to produce a reaction mixture containing aromatics boiling above 300° F., separating from the reaction mixture resulting from the catalytic operation a fraction boiling mainly below 300° F., and a fraction boiling mainly within the range of 300-500° F. and containing over 25 per cent aromatics, thermally reacting the last-named fraction without substantial admixture with hydrocarbons derived from any other source to produce a substantial percentage of olefins without substantial transformation of contained aromatics to lower boiling aromatics, separating from the reaction mixture resulting solely from thermally cracking said last-named fraction a fraction boiling mainly below 300° F. and containing substantially no aromatics and a fraction boiling mainly within the range of 300-500° F. and containing a high percentage of aromatics, and catalytically reacting this last-named fraction in an independent zone in the presence of a cracking type catalyst to greatly reduce the percentage of olefins and to produce aromatics boiling below 350° F., then separating

from the reaction mixture resulting from the second catalytic reaction a fraction boiling mainly below 350° F. of which aromatics comprise the major part.

19. The process defined in claim 18 comprising also subjecting the fraction boiling mainly below 300° F. which was separated from the reaction mixture resulting from the first catalytic operation to a further independent catalytic reaction in the presence of a cracking type catalyst to produce aromatics boiling above 300° F., separating from the reaction mixture resulting from this catalytic operation a lighter fraction, a heavier fraction and an intermediate fraction boiling mainly within the range of 300-470° F. and containing a major percentage of aromatics, independently catalytically reacting the intermediate fraction in the presence of a cracking type catalyst to transform higher boiling aromatics to aromatics boiling below 350° F., then separating from the reaction mixture resulting from this catalytic operation a fraction boiling mainly below 350° F. of which aromatics comprise a major part.

20. The process of producing a blending stock for gasoline nearly free of olefins and which contains a major proportion of aromatic hydrocarbons and a minor proportion of paraffins and naphthenes, which comprises producing, by catalytic cracking, from a hydrocarbon fraction having a boiling range mainly within the range 400-800° F., a hydrocarbon mixture a fraction of which boils mainly within the range of 300-470° F. and contains between 25 and 60 per cent relatively high boiling aromatic hydrocarbons boiling mainly above 300° F., then fractionating said mixture to separate said fraction, then, by thermally cracking said fraction, without substantial admixture with other hydrocarbons, transforming non-aromatic hydrocarbons contained therein to chemically different hydrocarbons including olefins and producing a hydrocarbon mixture a fraction of which boils mainly within the range of 300-470° F. and contains a higher percentage, between 40 and 65 per cent, than the first-named fraction, of aromatic hydrocarbons boiling mainly above 300° F., then fractionating the last-named mixture to separate the last-named fraction, then by catalytically reacting the last-named fraction in the presence of a cracking type catalyst, without substantial admixture with other hydrocarbons and separately from and independent of the first-named catalytic cracking step, transforming higher boiling aromatics to lower boiling aromatics and greatly reducing the olefin content, and then separating from the mixture resulting from the last-named catalytic reaction a fraction containing a higher percentage, between 65 and 85 per cent, of aromatics than the second-named fraction a high proportion of which aromatics boil below 300° F.

21. Process according to claim 20 comprising also producing in the first-named catalytic operation a gasoline fraction boiling mainly below 300° F., then by catalytically reacting this gasoline fraction in the presence of a cracking type catalyst and in an independent catalytic oper-

ation, producing a hydrocarbon mixture containing aromatics boiling above 300° F., then fractionating said hydrocarbon mixture to obtain a fraction boiling mainly within the range of 300-470° F. and containing a major percentage of aromatics, then by catalytically reacting the last-named fraction in the presence of a cracking type catalyst and in an independent catalytic operation, transforming the aromatics contained in
